UNITED STATES PATENT OFFICE.

WARREN F. MILLS, OF SAN FRANCISCO, CALIFORNIA.

BOAT-DAVIT.

1,329,921.

Specification of Letters Patent.

Patented Feb. 3, 1920.

Application filed July 30, 1919. Serial No. 314,199.

To all whom it may concern:

Be it known that I, WARREN F. MILLS, a citizen of the United States, residing in the city and county of San Francisco and State 5 of California, have invented new and useful Improvements in Boat-Davits, of which the following is a specification.

This invention relates to boat davits.

It is the principal object of the present 0 invention to provide a davit structure which will familiarly support a boat in a rigid manner and which will permit the boat to be instantly freed from its position at rest and lowered into the sea, without difficulty and 5 without danger of overturning.

The present invention contemplates the use 0 of davit posts upon which davits are pivoted; said davits being rigidly connected and supporting a boat so that both davits may 5 be swung simultaneously to effect the lowering or raising operation. The structure being further provided with a rigid canopy adapted to normally cover the top of the boat and which may be instantly moved 5 from its covering position when desired.

The invention is illustrated by way of example in the accompanying drawings, in which:—

Figure 1 is a view in side elevation illustrating the boat davit structure as mounted upon the deck of a ship and supported upon the upper deck thereof.

Fig. 2 is a view in section and end elevation, showing the boat davit in its position at rest and its operative position, as indicated by dotted lines.

In the drawings, 10 indicates the main deck of a ship while 11 designates the upper deck here shown as supported thereabove by means of deck posts 12. Mounted upon the upper deck and spaced a desired distance from the edge thereof, are a pair of davit posts 13 and 14. These posts are spaced a distance from each other slightly greater than the length of a boat 15. Extending horizontally between the posts is a keel block 16 upon which is mounted a hinged keel rest 17. This member is formed with a horizontal supporting surface 18 and a vertical ledge 19 adapted to stand along the rear side of the keel 20 of the boat 15. The keel support 17 is shown in Fig. 1, as being fitted with hinges 21 by which it is secured to the keel blocks and as shown in Fig. 2, this block is so disposed in relation to the keel support as to provide no obstruc-

tion to the downwardly and outwardly swinging action of the support.

The stem and stern of the boat 15 are fitted with suitable fall rings 22 which are 60 engaged by boat hooks or other fastening members. The hooks are supported by suitable cables 23 and 24, which are led upwardly and over blocks 25. The blocks 25 are secured upon the outer swinging ends of 65 davits 26 and 27. These davits are secured to the posts, by means of pins 28, and thus produce the proper swinging action of the davits and the levers connected therewith. As more clearly shown in Fig. 2 of the 70 drawings, it will be seen that the upper ends of the davit members are curved outwardly so that suitable clearance will be provided for the boat. The cables, after having passed over a pulley 25, extend through 75 blocks 29 secured to the outer side of the posts 13 and 14, by shackle members 30. This construction permits the shackle blocks 29 to swing freely and to adapt themselves to the angular position assumed by the 80 cables after passing through the blocks and to the pulleys on the ends of the davits. The cables are then led downwardly through an opening in the upper deck 10 and are wound around cable-drums 31 and 32. 85

These drums are mounted upon a horizontally extending shaft 33. The shaft is in turn rotatably supported within standards 34 and 35 fixed upon the lower deck. The shaft may be rotated by means of cranks 36 90 and 37, which are fixed to the opposite ends thereof and thus provide means whereby combined force may be exerted upon the shaft.

In order to retard the rotation of the shaft 95 when the davits are falling with the boat, a brake drum 39 is secured thereto and is provided with a brake band 40. The brake band 40 is extended downwardly to engage a lever arm 41. This arm is mounted upon 100 a pivot pin 42 and is formed integral with a hand-lever 43. The lever 43 extends along the floor and is fitted with a handle, by which pressure may be exerted by the operator on the crank 36. This hand lever is pivoted from the deck at a point 44. It will thus be evident that by drawing the brake band downwardly through a guide 45, it will be tightened and the rotation of the 105 shaft retarded, as well as the falling action 110 of the boat. The opposite end of the shaft is fitted with a ratchet wheel 46 which is

adapted to operate in conjunction with a ratchet member 47 to lock the shaft in any determined position and to hold it against the weight of the boat or any other burden 5 exerted upon the falls.

In order to hold the boat rigidly upon the keel support and at the same time to hold the keel support in its rigid position, the davits have been formed with right 10 angled lever arms 48, one of which is formed integral with each davit and is connected with an extension of the davit which projects through the floor of the deck 10. This lever portion is provided with a pair 15 of lock-bars 49, which are intended to project upwardly through slots 50 in the keel support and to stand parallel to the ledge 19 upon the back side of the keel. The locking position is clearly shown in Fig. 20 1. The lower end of these lock-bars 49 are pivotally mounted upon pins 51, which are carried by short lever arms 52. These lever arms are in turn fixed upon a horizontally 25 extending lock shaft 53, which is pivotally mounted by its opposite ends within the extension levers 48 of the davit. The outer end of the shaft 53 is provided with a crank 54, so that the shaft may be independently rotated, if desired and will thus reciprocate 30 the lock-bars 49. Connecting rods 55 are pivotally connected to the shaft 53 and extend forwardly and upwardly to engage the supporting members 17, thus making it possible 35 for the keel support 17 to be swung downwardly simultaneously with downward movements of the lever extensions 48 and the withdrawal of the lock-bars 49. In order to facilitate in operating the lever extension simultaneously, the forward ends of 40 these members are provided with a hand-rail 56, by which pressure may be exerted, either in a downward or upward direction.

A permanent and rigid cover member 57 is mounted over the top of the boat in the 45 place of the ordinary tarpaulin. This member is preferably made of sheet metal and is adapted to fit snugly over the top of the boat and around the edges thereof to prevent the inflow of water or the actions of 50 the elements. Bracket members 58 are secured to the centers of the cover and are adapted to receive screws 59. These screws extend upwardly through a cross-beam 60, which is fixed by its opposite ends to the 55 upper ends of the posts 13 and 14, and act to rigidly secure the boat.

In operation, it will be assumed that the boat davits are supporting the boat 15 in the position as shown in Fig. 2 and that the 60 keel of the boat is resting upon the support member 17; at the same time the keel is locked in this position by the obstruction afforded by the bars 49. When it is desired to lower the boat the hand-rail 56 may be 65 grasped to swing the lever extension 59

downwardly in the direction of the arrow *a*, as shown in Fig. 2. At this time the davits will swing outwardly and downwardly from their pivots 28 and in the direction of the arrow *b*. As the lever extensions 49 swing downwardly, they will, of course, draw downwardly upon the lock-bars 49 and at the same time will draw downwardly upon the connecting rods 55. The result of this action will be that the bars and the keel supporting member 17 will be drawn downwardly. This will act to throw the keel of the boat outwardly and insure that it will move in proper alignment with the davits from which it is supported. The davit, of course, cannot be lowered until after the ratchet pawl 47 has been released to permit rotation of the shaft 33. After this ratchet has been released the davits will fall simultaneously, due to their rigid connection through the end rail 56 and their pivots 28. The rate of fall of the boats may be controlled by pressure upon the hand lever 48 as it operates the brake band 40. It will be evident that the lock-bars 49 may be of such a length as to not be readily drawn from their locking position by the swinging of the lever extensions 48 and in that case the lever 54 may be drawn downwardly to independently operate the lock-bars and thereby secure a sufficient reciprocable movement. When the boat is to be restored to its original position, the falls are fastened by the hooks to the rings 22 at the stem and stern of the boat and thereafter the levers 36 and 37 may be rotated to wind the cable 23. As the cable is drawn upwardly, the davits will also be drawn and this action may be assisted, if desired, by an upward and forward pushing action upon the end-rail 56. When the davits are thrown outwardly and downwardly by this lever extension, it will be seen that the boat will be instantly swung clear of the supporting rig and carried over the side of the ship.

When the boat is in its original position between the posts, the extension 48 of the davits will extend directly beneath the floor of the boat. In this position, the drums may be locked against rotation by the pawl and ratchet 46 and 47, after which the cover may be forced downwardly over the top of the boat to its original position. The cover structure whether frame or sheet metal may then be clamped in position and will hold the boat rigidly without further securing devices.

It will thus be seen that the structure here provides for the rigid support of a boat from its davits when not in use and for the protection of the boat by a permanent covering as well as means whereby the davits may be simultaneously swung downwardly and the boats swung completely free of any supporting devices, the operation of all the

members being simple and direct in their action.

While I have shown the preferred form of my invention as now known to me, it will be understood that various changes in the combination, construction and arrangement of parts may be made by those skilled in the art, without departing from the spirit of the invention, as claimed.

10 Having thus described my invention, what I claim and desire to secure by Letters Patent is:—

1. In a device of the character described, a pair of vertically swinging davits, a vertically swinging keel support adapted to receive a boat, means acting in conjunction with said support for locking the boat thereupon, tackle sets carried over the davits and adapted to be secured to the boat, independent means for operating said keel lock, and means for simultaneously throwing the davits outwardly and swinging the keel support free of the boat.

2. In a device of the character described, a pair of rigid vertical posts, a pair of davits pivoted at said posts, tackle sets connected to the upper end of the davits and posts and carrying cables extending downwardly from the posts, the opposite ends of said cables adapted to be detachably secured to the stem and stern of a boat, a keel block disposed between said posts, a keel support hinged to said block and upon which the keel of a boat is adapted to rest, a vertical flange formed upon one side of said support and extending along the keel of the boat, lock members adapted to project through the keel support and obstruct the movement of the keel therefrom, right-angled lever extensions formed as continuations of the davits, and means operable by the swinging of said levers whereby the keel will be completely released and the davits thrown outwardly to lower the boat.

3. In a device of the character described, a pair of rigid vertical posts, a pair of davits pivoted to the posts, tackle sets connected to the upper end of the davits and posts and carrying cables extending downwardly from the posts, the opposite ends of said cables adapted to be detachably secured to the stem and stern of a boat, a keel block disposed between said posts, a keel support hinged to said block and upon which the keel of a boat is adapted to rest, a vertical flange formed upon one side of said support and extending along the keel of the boat, lock members adapted to project through the keel support and obstruct the movement of the keel therefrom, right-angled lever extensions formed as continuations of the davits, means operable by the swinging of said levers whereby the keel will be completely released and the davits thrown outwardly to lower the boat, and brake means

for controlling the movement of the davits and paying out the cable.

4. In combination with boat davits, swingable means engaging one side of the keel, vertically reciprocable means engaging the other side of the keel, and means to simultaneously swing said swingable means and to move said reciprocable means out of engagement with the keel.

5. Boat davits comprising a pair of spaced vertical posts, a pair of davits pivoted one to each of said posts, tackle blocks secured at the upper end of the posts and davits, cables passing over said blocks to engage the stem and stern of a boat by their ends, brake drums around which the opposite ends of said cables are adapted to be wound, a single shaft to which said drums are fixed, a ratchet member controlling rotation of said shaft, braking means upon the shaft adapted to control the movement of the davits and the cables, a rigid keel support disposed between the posts and upon which a boat is adapted to rest, means for locking the boat upon said support, and members operating in unison with the swinging davits for ejecting and releasing the boats from said support.

6. In a device of the character described, vertical posts, davits pivoted thereto and adapted to support a boat, a cross beam carried by a vertical support, and a boat cover supported by the cross beam and rigid means between the beam and cover to hold the latter over the top of the boat to form a closure therefor.

7. In a boat davit construction, a keel block, a keel support extending longitudinally of said block and hinged thereto and upon which the keel of a boat is adapted to rest, and means for swinging said support outwardly and downwardly to permit the boat to move freely from its normal inoperative position.

8. In a device of the character described, the combination with a pair of boat davits of clamping means adapted to fit into the top of a boat supported thereby and rigid means above the clamping means to rigidly secure the boat against movement without the requirement of further fastenings.

9. In a device of the character described, the combination with a pair of boat davits of a cover frame adapted to positively engage the top of a life boat and rigid means above the frame for securing said frame in position to prevent movement of the boat in relation to the davits.

10. In combination with boat davits, swingable means engaging one side of the keel, vertically reciprocable means engaging the other side of the keel, a shaft connected to each of said means, and means to actuate the shaft to effect simultaneous movement of each of said means.

11. In combination with pivoted davits having angular extensions, a pair of means engaging the keel on opposite sides thereof, means connected to said extensions and to the outer of said pair of means to release the keel from said outer means, and means connected to said extensions and to the inner of said pair of means to simultaneously actuate said inner means to move the keel outwardly of the vessel.

12. In combination with boat-carrying davits, vertical posts, a cross-beam rigidly supported by the posts, a cover for the boat, adjustable devices interposed between the cross-beam and cover for forcibly holding the latter in place, and means to actuate the davits.

13. In combination with boat-carrying davits, a swingable keel support upon which the keel rests, and means to actuate the support to cause same to move the boat outwardly and out of keel supporting position.

14. In combination with boat-carrying davits, a swingable keel support upon which the keel rests, means coöperating with the keel support to lock the keel thereto, and means to actuate the support to cause same

to move the boat outwardly and out of keel supporting position and to simultaneously move said locking means to inoperative position.

15. In combination with boat-carrying davits, means engaging the keel on the inner side thereof, locking means engaging the keel on the outer side thereof, and means to render the locking means inoperative and to simultaneously move the keel engaging means outwardly.

16. In combination with boat-carrying davits, means engaging the keel on the inner side thereof, locking means engaging the keel on the outer side thereof, means operated by the davits to render the locking means inoperative, and means operated by the davits to simultaneously move the keel engaging means outwardly.

In testimony whereof I have hereunto set my hand in the presence of two subscribing witnesses.

WARREN F. MILLS.
